ELECTRIC DISCHARGE LAMP

Edward B. Noel and John L. Falconer, Jr., Cleveland Heights, Ohio, assignors to General Electric Company, a corporation of New York

Application August 29, 1952, Serial No. 307,082

6 Claims. (Cl. 313—184)

This invention relates to electric discharge lamps containing an ionizable medium including a metal vapor and an inert starting gas. It is more particularly concerned with high pressure discharge lamps in the form of elongated and relatively slender tubes which, by reason of conventional mode of manufacture, may be somewhat irregular in diameter along their length.

In the design of photochemical lamps suitable for phototyping on sensitized paper, sometimes known as whiteprinting, it is desirable to provide a lamp in the form of an elongated tube having high radiation efficiency at 3650 Å. with substantially uniform intensity of radiation per unit length of the lamp. The necessity for substantial uniformity arises by reason of the fact that in the whiteprinting process, the sensitized paper passes immediately below the lamp, moving in a direction transverse to the length of the lamp. If the radiant output is not substantially uniform per unit length of lamp, the printing will be uneven and will be streaked with darker bands corresponding to the regions of lower output. Thus a line source of substantially uniform radiation is required.

In order to realize good efficiency at 3650 Å., the electric discharge is effected through mercury vapor at a relatively high pressure, for instance at $\frac{1}{4}$ to 5 atmospheres. A high mercury pressure of course entails a high operating temperature so that it is necessary to utilize for the envelope of the lamp a material such as quartz capable of withstanding the high temperatures involved. But when lamps were made having an envelope of commercial straight drawn quartz tubing and containing the usual filling of mercury with argon as a starting gas, it was found that the 3650 Å. output of such lamps was extremely non-uniform along the length of the lamp. It was also found that the non-uniformity could be corrected by utilizing precision bore or sized quartz tubing. However such quartz tubing is prohibitively expensive, costing for instance twice as much as the commercial drawn tubing whereof the cost is already a substantial part of the total cost of the lamp.

Accordingly the object of the present invention is to provide a new and improved lamp of the type discussed above and having substantial uniformity of radiant output per unit length thereof, without using precision bore or sized tubing for the envelope.

Another object of the invention is to provide a new and improved elongated source of 3650 Å. radiation having substantial uniformity of radiant output along its length and having an efficiency superior to that heretofore realizable.

In the course of the studies which culminated in the present invention, we discovered that the non-uniformity in radiant output per unit length in lamps made of commercial straight drawn quartz tubing was associated with variations in diameter of the tubing along the length

2

thereof. Ordinary commercial straight drawn quartz tubing may vary in diameter up to 20%, and non-uniformity was observed in tubing varying in diameter as little as about 5%. We further discovered that the non-uniformity of 3650 Å. output in such tubes was associated with the use of a starting gas such as argon. When the filling pressure of the starting gas was reduced, the non-uniformity also decreased, and, in a lamp containing only mercury without any starting gas, it substantially disappeared. It will be appreciated however that a commercially practical lamp requires a starting gas in order to have a reasonably low starting voltage and short warm-up time. We further discovered that for a lamp having a given starting gas filling pressure, the non-uniformity became more pronounced as the loading, that is the wattage input into the lamp, was increased.

We have found that the non-uniformity of radiation is associated with variations in the partial pressures of the mercury vapor and of the starting gas along the length of the lamp. Throughout the whole length of the lamp, the partial pressure of each component is a substantial fraction of the total pressure. The total pressure in the lamp at any one time is constant throughout the lamp; however in the regions of smaller diameter where the 3650 Å. radiation decreases, the partial pressure of the starting gas is a greater percentage of the total pressure, and the partial pressure of the mercury is proportionately less. For instance, the partial pressure of mercury may vary by as much as 1 to 2.5 as between regions of smaller and larger diameter. It was also observed that the spectral distribution of the radiation in the regions of high 3650 Å. output shows a higher arc temperature, and conversely the arc temperature is lower in the regions of low 3650 Å. output. Proceeding on these discoveries, it was theorized that the non-uniformity might be reduced by using a starting gas having a lesser thermal conductivity so as to reduce its cooling effect upon the arc in the regions of small diameter. It was then found in fact that when krypton is used as the starting gas, the uniformity is improved and when finally xenon is substituted for the filling gas, a substantially uniform output is realized. Furthermore, with xenon as the starting gas, not only is a uniform output achieved, but the efficiency of the lamp unexpectedly improves by as much as 10% beyond what has previously been considered the maximum possible efficiency, namely the efficiency of the lamp containing only mercury vapor without any starting gas whatsoever.

For a fuller understanding of the invention and of the advantages which may be realized through it, attention is now directed to the following description and accompanying drawings. The features of the invention believed to be novel will be more particularly pointed out in the appended claims.

55 In the drawings:

Fig. 1 is a side view of a form of lamp embodying our invention.

Fig. 2 is a sectional view of one end of the lamp showing the electrode and seal structure.

60 Fig. 3 is a graph illustrating typical variations in diameter of commercial straight drawn quartz tubing such as that of the lamp of Fig. 1, along the length thereof.

Fig. 4 is a graph illustrating light output along the length of a lamp for various pressures of argon gas filling.

Fig. 5 is a graph illustrating the variation in light output along the length of a lamp for various wattages.

Fig. 6 is a graph illustrating the light output along the length of a lamp containing different starting gas fillings.

Referring to Figs. 1 and 2, the lamp illustrated therein

comprises an elongated slender tubular envelope 1 having thermionic electrodes 2, 2' sealed into opposite ends thereof, and containing a small quantity of mercury represented by the droplet 3, together with a filling of an inert gas, which, in accordance with the invention, will include a substantial proportion of xenon. In Fig. 1, the lamp is shown with a central portion of the envelope removed in order to facilitate the illustration: in an actual construction, the lamp may have an internal diameter of 10 mm. and a length of 125 cm. The electrodes 2, 2' may be of any suitable type, preferably either activated with electron emissive material such as alkaline earth oxides or having other electron emissive materials such as thorium associated therewith. As illustrated in the drawing, the electrode comprises a tungsten rod 4 projecting into the end of the envelope which is somewhat reduced in diameter, and having wound about it a tungsten slip-over coil 5. A narrow strip or sliver of thorium metal (not visible in the drawing) is enclosed within the coil or helix 5, being laid alongside the tungsten rod 4. The other end of the tungsten rod 4 is welded to a tungsten foil 6 which makes a hermetic seal to the quartz, the quartz being collapsed about it at the end of the lamp.

The invention is of particular value in the case of a tube or envelope 1 made of a vitreous material varying appreciably in diameter. For instance the tube may be made of commercial straight drawn quartz of approximately 10 millimeters inside diameter which, in accordance with ordinary commercial manufacture, may vary in diameter up to about 20%. Referring to Fig. 3, curve 11 illustrates the variation in diameter of a typical tube about 48 inches (125 cm.) long along the length thereof. The range of variation for this lamp is approximately 10% and this is fairly typical of commercial drawn quartz tubing. It will be observed that the variations appear as short irregular jumps which are superimposed upon relatively long sweeps producing a peak at 5 inches and another at 35 inches approximately. The long sweeping variations are the ones which apparently cause the non-uniformity of output; the short term irregular variations do not appear to have any noticeable effect upon the uniformity of the discharge. The 3650 A. radiation will exhibit a pattern corresponding in general to the long sweeping variations in diameter. As a rule, it appears that variations in diameter will tend to cause non-uniformity of output when the cycle of variations or distance between successive peaks or valleys exceeds 15 times the inside diameter of the tubing. The variations may be as large as 20% of the internal diameter of the tubing, the effect on the non-uniformity varying of course with its magnitude. In precision bore or sized tubing, the variations do not exceed 1 to 2%, and non-uniformity of 3650 A. output then ceases to be a problem.

The curves of Fig. 4 illustrate the relative 3650 A. radiation for various pressures of argon as the starting gas. Curves 21, 22, 23 and 24 show the relative output for 25, 12½, 6 and 0 millimeters of argon respectively. It will be observed that reducing the pressure of the argon has two effects: firstly the over-all output of the lamp increases, and secondly the non-uniformity becomes less pronounced, and substantially disappears in the case of 0 millimeter of argon, that is, when no starting gas is included in the lamp. It will be appreciated of course that as the argon pressure is reduced, the warm-up time that is the time of the lamp without any increases. Thus in the case of the lamp without any starting gas, the lamp was started by heating it with a torch so as to raise the mercury vapor pressure sufficiently to allow the establishment of a discharge. Of course in a lamp for commercial use, such an expedient is impractical so that a reduction of the filling pressure of the starting gas does not afford an acceptable solution to the problem of reducing non-uniformity of output.

Referring to Fig. 5, curves 31, 32 and 33 illustrate the relative 3650 A. radiation for this type of argon

filled lamp under wattage inputs of 2200, 1400 and 1000 watts respectively. Although the non-uniformity decreases fairly rapidly as the wattage input is decreased, the total radiant output decreases at a rate which is greater than the decrease in wattage. Thus although it is possible to reduce the non-uniformity by reducing the wattage input, no real solution is afforded because the efficiency of the lamp drops more than can be tolerated.

The non-uniformity effects described above were first noted in lamps of the general configuration of that illustrated in Fig. 1, comprising a quartz arc tube of approximately 10 mm. inside diameter and defining an arc gap approximately 125 cm. (48 inches) long. The nominal wattage, voltage, and current of this lamp are 1400 watts, 1675 volts and 1.0 ampere respectively. It will be appreciated that the actual wattage is somewhat less than the product of volts by amperes by reason of the non-sinusoidal waveform of the current. The quantity of mercury is such as to be all vaporized when these operating conditions are attained, in accordance with the teachings of U. S. Patent 2,247,176, Pirani et al. For the lamp described, the quantity of mercury is approximately 95 milligrams. The starting gas filling of these lamps previous to the invention was argon gas at approximately 25 millimeters pressure at room temperature. Our studies indicated that the non-uniformity of 3650 A. output under those conditions became appreciable when the variations in diameter of the tubing exceeded 2%, and in order to utilize commercial drawn quartz tubing, variations in diameter of as much as 20% had to be taken into account. These variations in diameter are significant when they occur over a cycle, that is over a length between successive maxima or minima exceeding 15 times the inside diameter.

In accordance with our invention, it was found that when xenon is employed as a starting gas, the 3650 A. radiation of the lamp becomes substantially uniform even at pressures of xenon as high as about 40 mm. of mercury. These results are illustrated in Fig. 6 wherein curve 41 shows the relative 3650 A. radiation for a lamp such as has been described and containing argon as the starting gas at 25 mm. pressure. When the same lamp is resealed with xenon at 25 mm. pressure, the relative 3650 A. radiation becomes substantially uniform over the whole length of lamp as illustrated by curve 42. It will be appreciated that the curves of Fig. 6 were measured from another lamp than that illustrated by the diameter variation characteristic of Fig. 3. The lamp from which were measured the curves of Fig. 6, as will appear upon inspection, had a maximum diameter near the center and minimum diameters at the ends, such being the reverse of the lamps from which characteristics of Figs. 4 and 5 were measured. However the range of variations in diameter is substantially the same in all instances and like results are obtained.

In addition to the improvement in uniformity of 3650 A. output, the substitution of xenon for argon quite unexpectedly gives an appreciable increase in total light output over a mercury-argon mixture and even over mercury alone. The relative output for the same lamp not including any starting gas is illustrated by curve 43. It will be seen that the addition of 25 mm. of xenon actually gives an increase of approximately 10% in 3650 A. output over the theoretically optimum condition of no starting gas illustrated by curve 43.

Our further studies after the discovery of the remarkable improvements both as to uniformity and efficiency resulting from the use of xenon and forming the basis of the present invention, have indicated that the phenomenon of non-uniformity of radiant output in the prior art lamps is associated with variations in the partial pressures of the mercury vapor and of the filling gas throughout the length of the tube. To test this hypothesis, the partial pressure of the mercury was measured at the positions of maximum and minimum intensity on a lamp containing

argon as the starting gas. The partial pressure of the mercury in a particular region of the lamp may be determined by cooling a small area of the bulb wall in that region and measuring the temperature at which the mercury started to condense out. The condensation of the mercury may readily be determined by means of a photometer which measures the intensity of the radiation from the region in question; as soon as mercury begins to condense, the intensity of radiation starts to drop. The measure of the condensation temperature of the mercury gives of course a measure of the mercury pressure, and the results indicated that the mercury pressure varied by as much as 2.5 to 1 as between regions of maximum and minimum diameter. These results were confirmed by measuring the spectral distribution of the radiation as between these different regions. The spectral distribution showed a considerably higher arc temperature in the regions of maximum diameter than in the regions of minimum diameter.

Our findings point to the conclusion that in a relatively long and slender discharge tube having variations in diameter of the order described, non-uniformity of radiant output will occur inasmuch as the loading is such that the partial pressure of the mercury and the partial pressure of the starting gas are both substantial fractions of the total partial pressure, provided further that the said starting gas has a substantial cooling effect upon the arc. In applying this rule, it must be kept in mind that the pressure of the starting gas increases directly with the absolute temperature of the lamp. For instance, when the lamp considered here is filled with argon at 25 mm. at room temperature and operated at an average internal temperature of approximately 2700° C., the total pressure of the mercury vapor and argon is approximately eleven hundred millimeters. However at this temperature, the argon pressure has increased approximately 10 fold and becomes approximately 250 mm., the mercury vapor of course exerting the remaining 850 mm. of pressure. Thus in this specific instance, the argon filling exerts approximately one-quarter of the total pressure and the mercury exerts three-quarters thereof. In such a lamp, the non-uniformity of 3650 A. output is very pronounced whenever the tubing has variations in diameter of the order in question here. In general it appears that the phenomenon will occur under the stated condition when the starting gas exerts, during operation of the lamp, a partial pressure between 5% and 75% of the total pressure exerted by the starting gas and the mercury vapor. Further experiments have indicated that non-uniformity effect may be just as pronounced with a 25 mm. diameter lamp as with 10 mm. diameter lamp when both have the same percentage diameter variation. In general, it appears that non-uniformity becomes a serious factor under the stated conditions with discharge lamps having an arc voltage drop and loading in excess of 4 volts and 5 watts respectively per centimeter length of the envelope.

In accordance with the invention, the undesirable non-uniformity characteristic may be substantially reduced or even eliminated under the stated conditions by using a starting gas such as xenon having a lower thermal conductivity than argon. Our experiments have confirmed that at least for the inert gases neon, argon, krypton and xenon (named herein in decreasing order of thermal conductivity) the non-uniformity is most pronounced with neon and least or substantially non-existent with xenon. Helium appears to provide an exception since being the lightest in atomic weight and hence having the highest thermal conductivity, it would be expected that the non-uniformity would be most pronounced; in fact, the opposite is true and helium gives a very uniform output although the efficiency of production of 3650 A. radiation is too low for a commercial lamp. The explanation for this may reside in the fact that helium has a very high diffusion coefficient so that it may be impossible for the segregation of helium and

mercury in the various portions of the tube to occur. The theoretical explanation which has been proposed would also appear to indicate that radon having a higher atomic weight than xenon and hence a lower thermal conductivity, would be superior even to xenon in achieving a uniform output. However due to the scarcity of radon, its radioactive character, and its short half-life, it is not suitable as a starting gas for a commercial lamp.

While a certain specific embodiment of the invention has been shown and described in detail, it will be understood that the invention is equally applicable to lamps falling within the stated ranges of parameters and the appended claims are intended to cover any such modifications which come within the true scope and spirit of the invention.

What we claim as new and desire to secure by Letters Patent of the United States is:

1. A high pressure gaseous electric discharge lamp forming a line source of radiation comprising an elongated tubular envelope having a length at least 15 times its diameter and having diameter variations greater than 2% occurring along the length of said lamp with a cycle extending over at least 15 diameters and the internal diameter of said envelope being in the range of approximately 10 to 25 millimeters, a pair of electrodes sealed into opposite ends of the envelope, and an ionizable atmosphere therein comprising a starting gas and mercury vapor, the quantity of said starting gas being proportioned such that its partial pressure at the operating temperature of the lamp is a substantial fraction of the total pressure exerted by the said starting gas and the mercury vapor, the said starting gas comprising predominantly an inert gas having a thermal conductivity less than that of argon whereby the radiant output is substantially uniform per unit length of lamp irrespectively of the said variations in envelope diameter.

2. A lamp as in claim 1 wherein the inert starting gas is predominantly xenon.

3. A lamp as in claim 1 wherein the quantity of the starting gas is such as to exert a partial pressure at the operating temperature of the lamp which lies in the range of 5% to 75% of the total pressure developed by the said starting gas and mercury vapor and the quantity of mercury is sufficient to produce at normal operating temperature a voltage drop between the electrodes in excess of 4 volts per centimeter with a loading of 5 watts per centimeter length of lamp.

4. A lamp as in claim 1 wherein the quantity of the starting gas is such as to exert a partial pressure at the operating temperature of the lamp which lies in the range of 5% to 75% of the total pressure developed by the said starting gas and mercury vapor, the quantity of mercury is sufficient to produce at normal operating temperature a voltage drop between the electrodes in excess of 4 volts per centimeter with a loading of 5 watts per centimeter length of lamp, and the starting gas is predominantly xenon.

5. A lamp as in claim 1 wherein the lamp is operable with a wattage input not less than 5 watts per centimeter length thereof to develop a total pressure in the range of $\frac{1}{4}$ to 3 atmospheres, the quantity of said starting gas is proportioned such that the partial pressure exerted thereby under normal operating conditions of said lamp is a substantial fraction of the total pressure of said starting gas and mercury vapor, and the said starting gas consists predominantly of xenon at a pressure in the range of a few centimeters whereby to realize a total radiant output exceeding that realizable without any starting gas in the envelope.

6. A lamp as in claim 1 wherein the lamp is operable with a wattage input not less than 5 watts per centimeter length thereof and a voltage drop not less than 4 volts per centimeter length to develop a total pressure in the lamp of $\frac{1}{4}$ to 3 atmospheres, the quantity of mercury being proportioned to be totally vaporized under the

operating conditions and the quantity of said starting gas being proportioned such that the partial pressure exerted thereby under normal operating conditions of said lamp is a substantial fraction of the total pressure of said starting gas and mercury vapor, and the starting gas consists predominantly of xenon at a pressure in the range of a few centimeters whereby to realize a total radiant output in excess of that realizable without any starting gas in the envelope.
